BIOCHEMICAL PROCESSES FOR THE OXYGENATION OF STEROIDS

Oscar Hechter, Worcester, Robert P. Jacobsen, Shrewsbury, Roger Jeanloz, Harold Levy, and Gregory Pincus, Worcester, and Victor Schenker, Shrewsbury, Mass., and Victor Marshall, Chicago, Ill., assignors to G. D. Searle & Co., Chicago, Ill., a corporation of Illinois

No Drawing, Application January 25, 1951,
Serial No. 207,826

11 Claims. (Cl. 195—51)

This invention relates to processes for introducing a hydroxyl substituent into a steroid at the 11-position. More particularly this invention relates to methods of introducing an 11 β -hydroxyl group into certain steroids by perfusing their dilute solutions through lacerated excised adrenal glands under such conditions that the glands are maintained in a functioning state, whereby an 11 β -oxy radical is formed by biochemical processes in said steroids with the conversion of the latter to hormones useful as medicinal agents and intermediates therefor.

By our process it is possible to convert 11-desoxycorticosterone, which has the formula

into corticosterone heretofore available only in minute amounts from animal adrenal glands.

It is likewise possible by our methods to introduce a hydroxyl group of the β - or natural configuration into the 11-position of 11-desoxy-17-hydroxycorticosterone, which has the formula

thereby forming 17-hydroxycorticosterone, of the formula

which is one of the most important and pharmacologically useful hormones of the adrenal gland, but likewise heretofore available in only very minute amounts from natural sources.

Certain other steroids can be bio-oxygenated by the methods of this invention, such as androsterone which forms 11 β -hydroxyandrosterone; 4-androstene-3,17-dione similarly treated forms the corresponding 11 β -hydroxy derivative. Progesterone by the methods of our invention is converted into a mixture of 17-hydroxycorticosterone, corticosterone, 11 β -hydroxyprogesterone, 17-hydroxycorticosterone and other sterols. Other steroids which can be bio-oxygenated include 17-hydroxyprogesterone, 11-desoxycorticosterone acetate, 11-desoxy-17-hydroxycorticosterone 21-acetate, isoandrosterone, dehydroisoandrosterone, 16-dehydropregnolone, Δ^4 -androstene-3, 17-dione, Δ^4 -pregnene-17,20,21-triol-3-one, Δ^5 -pregnene-3-ol-20-one and related pregnanediols and pregnanolones. Solubilized derivatives of these steroids, such as glucosides, hemisuccinates, and the like, can also be used.

By the methods of this invention it is also possible to 11-bio-oxygenate functional derivatives of the above-mentioned steroids such as the acetate or propionate. Thus 11-desoxycorticosterone 21-acetate and its corresponding 17 α -hydroxy derivative are converted by the methods of this invention into corticosterone and 17-hydroxycorticosterone respectively, the acetoxy group being hydrolyzed during the perfusion and isolation processes.

It will be apparent to one skilled in the art that the 11 β -hydroxy steroids formed by the processes of this invention may be readily converted by known methods to the corresponding pharmacologically useful 11-oxo (oxidation) or 11,(12 or 9)-anhydro (dehydration) compounds whereas the reverse transformations, reduction of 11-oxo or hydration of 11,(12 or 9)-anhydro to 11 β -oxy compounds are extremely difficult or impossible to carry out.

Thus it can be seen that the processes or this invention for introducing the 11β -hydroxyl group into steroid hormones of the adrenal cortical type are of unique importance. 11β -hydroxy steroid hormones like corticosterone and 17-hydroxycorticosterone, and related hormones such as 17-hydroxy-11-dehydrocorticosterone and 11-dehydrocorticosterone affect the carbohydrate and protein metabolism by increasing the liver's store of glycogen. These hormones also increase the working capacity of isolated muscle. A most important use for 17-hydroxy-11-dehydrocorticosterone has been in the treatment of rheumatoid arthritis. The use of this substance in rheumatoid arthritis has resulted in improvement within a few days. Pain, stiffness and limitation of movement were reduced, and tenderness and muscular pain relieved. Appetite and weight improved and "toxicity" was replaced by a sense of well-being. The role of the hormone in other conditions such as myasthenia gravis and rheumatic fever is being studied.

It is the object of this invention to provide simple and relatively inexpensive methods for obtaining these 11β -hydroxy steroids and their derivatives from accessible starting materials. It is further an object to provide methods for producing 17-hydroxycorticosterone and related 11β -hydroxy compounds in a state of purity by simple and efficient biochemical methods. Another object is to provide methods of producing 11β -hydroxy steroids, such as 17-hydroxycorticosterone, which can be readily oxidized to 11-keto steroids, such as cortisone, by acetylation of the 21-hydroxyl radical followed by mild chromic oxide oxidation of the 11-hydroxyl radical. Other objects will be apparent to those skilled in the art.

According to our invention, excised mammalian adrenal glands are maintained in a functioning state by perfusion with an appropriate medium, natural or synthetic, at temperatures in the range of 35-40° C. and preferably at 36-37.5° C., and to the perfusion medium is added a quantity of steroid to be hydroxylated. After the medium has circulated through the gland at least once, the perfusate is removed and the hormones separated by suitable procedures. The perfusion medium can comprise blood, blood plasma with saline, or saline solutions of gelatin, technical blood albumin, synthetic plasma substitutes, and the like or mixtures thereof. For most successful operation, homologous plasma or whole blood or mixtures thereof constitute the most desirable perfusion media. Whole blood, before or after hemolysis or defibrination, or saline-diluted mixtures thereof are further preferably treated by being circulated through a liver preparation before use as a perfusion medium, though for short periods of perfusion this may not be necessary. This is desirable both in order to remove and to prevent formation of clots, and to remove vasoconstrictor substances present in these media which might interfere with the free flow of the perfusate through the organ. The perfusion medium may be supplied to a single gland under either pulsating or non-pulsating pressure or to a parallel bank of several glands under non-pulsating hydrostatic pressure. The pressures used have been in the range between 20 mm. of mercury and 200 mm. Generally pressures in the range of 20-100 mm. are preferred. The pulsations used have been at a rate of about 24 to 180 per minute. Whereas pulsating pressures

may be more physiological for the perfusion, steady hydrostatic pressures are also satisfactory. The length of the period of perfusion may vary from a fraction of an hour to several hours depending upon the rate of flow and the volume to be perfused. It is only necessary that the fluid containing the steroid pass through the functioning gland at least once. Additional cycles are useful for producing more of the oxygenated steroids particularly at the higher input concentrations of precursor. In practice we have found that the more rapid perfusions (0.5 to 7 liters/gland/hour) are quite satisfactory both as to conversion rate and purity of product; with faster flow rates the number of cycles may be increased. The concentration of the steroids in the perfusion medium may vary from 50 to 1000 mg. per 1000 ml. of perfusion medium. The preferred concentration is about 50-300 mg. per liter.

The adrenal glands which are used in our processes may be obtained from any of the common animals including the horse, sheep, pig, cattle, dog, rabbit, cat and monkey; those from the larger species are most convenient to use. The following illustrate the methods of preparing mammalian adrenal glands for use in our procedure:

A. *Intact gland arterial flow.*—A laparotomy is performed on an anesthetized or freshly killed animal and the kidney region exposed. The entire region of the paired adrenal glands is dissected. Two glands are removed from the kidneys of each animal, care being taken not to slash the gland. The gland is dropped at once into cold saline solution and used as soon as possible. Extraneous fat and tissue is removed from the gland and small venal entries near the main large vena cava are tied off. A cannula is inserted into the aorta just below the renal arterial branch supplying the adrenals or into any direct aortic branch to the adrenal region, and all of the extra-adrenal arteries are ligated. A buffered balanced salt solution may be washed through the cannulated preparation to remove all blood remaining in the vessels of the preparation but this is not absolutely necessary. The cannula is then affixed to the arterial entry of a perfusion pump designed to circulate the perfusion medium continually under either pulsating or nonpulsating hydrostatic pressure as specified above, and circulation of this medium is promptly started. It is essential that transfer of the cannulated preparation to the perfusion apparatus be as rapid as possible and that prompt perfusion be started with the medium at a pressure sufficient to insure active circulation through the glandular tissue. The above operations and perfusion are best conducted under completely sterile conditions in order to insure maximal survival of the glands, though for shorter periods of perfusion absolute sterility is not required. Practical sterility can be maintained by the addition to the medium of suitable concentrations of antibiotics such as penicillin and streptomycin.

B. *Intact gland venous flow.*—The dissected adrenal obtained as in A is trimmed to remove all of the extra-glandular tissue. A suture is looped around the neck of the adrenal vein and a cannula is pressed in and tied. By flooding the cannula with saline solution while massaging the gland, the system is freed of air. Saline supply under low pressure is passed through to flush out the gland. During this time all fat unem-

bianous tissue and the major residue of the wall of the vena cava are trimmed off. The gland is then stored in cold saline solution. The cannulated preparation is then washed with saline and the cannula affixed to a perfusion apparatus as above.

C. *Lacerated gland venous flow*.—The trimmed gland with venous cannulation as in B is subjected to multiple cortical laceration over virtually its entire surface, the cuts being spaced 0.5 to 3 mm. apart and made to a depth of about $\frac{1}{4}$ to $\frac{1}{2}$ the thickness of the cortical layer. Care is taken to lacerate the cortical layer only and to avoid the deeper medullar layer. When laceration is complete saline solution under a pressure of 20-50 mm. is applied to the cannula to check adequacy of flow. Following laceration the gland is attached to the perfusion apparatus, care being taken to avoid air bubbles. The perfusion medium is passed through the gland and the solution of the steroid is added to the supply reservoir of fluid. During the perfusion pressures of 20 to 70 mm. are maintained throughout and oxygen is continuously fed into the perfusion liquid. This type of preparation is particularly useful in banks of several glands each attached to a branch of a manifold type of perfusion apparatus utilizing nonpulsating flow under hydrostatic pressure.

The steroid hormones which are produced by our processes can be isolated from the perfusion medium by a variety of methods. The simplest is by direct adsorption with charcoal followed by elution of the charcoal with suitable solvents such as methylene chloride, ethylene chloride, benzene, chloroform, acetone, methanol, ethyl acetate and the like. Upon removal of the solvent, preferably by evaporation under vacuum at low temperature in an inert atmosphere, there is obtained a residue of the steroids. This residue is contaminated with a small fraction of the lipoidal material normally present in blood. Alternatively the perfusion medium may be dialyzed against saline solution and the latter treated with charcoal as above (or during the dialysis) or extracted directly with a solvent such as chloroform, methylene chloride, ethylene chloride and the like. The steroids which are in solution in the perfusate pass through the membrane and are about equally distributed between the medium and the saline solution. With charcoal in the saline during dialysis the steroids are rapidly adsorbed and the dialysis period shortened. This method has the advantage of avoiding contamination with lipoidal material, but is time-consuming. In the most convenient isolation procedure, the hemolyzed perfusate is stirred each day with about 5 g. per liter of activated charcoal for 3 to 6 days, the blood being decanted after settling of the charcoal. In small scale experiments the charcoal portions are combined and stored in saline at about 5° C. during the treating period, while on a larger scale the individual charcoal portions may be collected at once, washed with water or saline and dried. The dried charcoal is then exhaustively extracted with warm solvent disclosed above, such as methylene chloride, and the desired 11-oxygenated steroids are isolated in a relatively pure, semicrystalline form. Further extraction of the charcoal with warm benzene, or other suitable solvents mentioned above, may be resorted to, if necessary, to remove any remaining material. The product may be further purified by direct crystallization or by chromatographic resolution.

The preferred adsorbant for the latter method is silica gel in finely divided form.

As used herein, the term "oxygenation" refers to the introduction of an atom of oxygen into an organic compound, resulting in the formation of a hydroxyl radical. A formaldehydogenic steroid is one which contains an α -ketol or α -glycol group at the 20-21-position, which on periodic acid oxidation gives rise to formaldehyde.

Our invention is illustrated in detail by means of the following examples but is not to be construed as limited thereto. In these examples, volumes are reported as liters (l.) and milliliters (ml.), weights as grains (g.) and milligrams (mg.), pressures as millimeters of mercury (mm.), and melting points as degrees centigrade (° C.). The term "citrated blood" means 85 volumes of whole blood mixed with 15 volumes of citrate solution (an aqueous solution containing 1.6% sodium citrate and 5% glucose). The term "citrated saline solution" means an aqueous solution containing 0.8% sodium chloride and 0.35% sodium citrate. "Saline solution" means a solution of sodium chloride of 0.8 to 0.85% concentration.

Example 1

To a mixture of 500 cc. of plasma and 500 cc. of whole blood was added 2 cc. of propylene glycol containing 100 mg. of 11-desoxycorticosterone and the resulting solution was perfused with arterial flow through an intact beef adrenal gland at an average flow rate of about 0.5 liter per hour and a pulsing pressure of about 100 mm. of mercury. The perfusate was then hemolyzed by freezing and thawing, stirred for 30 minutes with 5 g. of activated carbon at room temperature and allowed to settle for several hours. The blood was decanted and the charcoal treatment repeated twice during a period of two days. The combined charcoal was collected, washed with saline solution and dried by washing with a little acetone. The air-dried material was then extracted in a Soxhlet apparatus with methylene chloride for twenty hours and the extract concentrated under diminished pressure under nitrogen. The residue consisted of 51 mg. of semicrystalline material containing 23 mg. of formaldehydogenic steroids (The Hormones, by Pincus and Thimann, vol. I, 1948, p. 613). The combined residue from 5 liters of perfusate processed as above was chromatographed on silica gel by eluting with benzene-ethyl acetate mixtures providing 64 mg. of crude crystalline corticosterone and 70 mg. of unaltered desoxycorticosterone.

The corticosterone fraction, after purification by recrystallization from ethyl acetate-neohexane, or ether-acetone-hexane, melted at 173.3-180° C. (powder) or 178-180.5° C. (intact crystals). The rotation in ethanol was $[\alpha]_D^{30} = +227^\circ$ (c. = 0.240). Mixed with authentic corticosterone isolated from natural sources, M. P. 173-179° C. (powder) or 176.5-181° C. (intact crystals), the perfusion product mixture melted at 173-181° C.

Acetylation of the perfusion product provided an acetate melting at 150.5-152.5° C., whose mixture with authentic corticosterone 21-acetate, M. P. 151.5-152.5° C., melted at 150.5-152° C.

Example 2

A solution of 100 mg. of desoxycorticosterone in 400 cc. of whole blood was perfused with arterial flow through an intact beef adrenal gland as in Example 1. 200 cc. of the perfusate was dialyzed against 2 liters of isotonic saline (0.85% sodium chloride solution) for three days at 2° C.

The saline solution was then extracted with chloroform and the solvent layer washed, dried and concentrated under diminished pressure under nitrogen. Analysis of the semi-crystalline residue by the periodic acid method indicated the presence of 21 mg. of formaldehydogenic steroid from the 100 mg. of desoxycorticosterone used. This material was assayed by the glycogen deposition test (Pabst et al., Endocrinology, 41: 55-65, July 1947) and was found active at the 500 microgram dosage level. This material was therefore approximately equivalent to 10 mg. of corticosterone.

Example 3

A solution of 150 mg. of desoxycorticosterone in 1500 cc. of plasma was perfused as in Example 1 for about 3 hours. The perfusate was then placed in viscose tubing and allowed to stand at 2° C., with gentle rocking, for about 2.5 days with 500 cc. of citrated isotonic saline (0.80% sodium chloride, 0.45% hydrated sodium citrate) containing 1.5 g. of activated charcoal. The charcoal was collected, washed with water, and extracted with acetone and benzene. The solvent solutions were evaporated under reduced pressure in a nitrogen atmosphere and the residue extracted with chloroform. The chloroform solution was dried with anhydrous sodium sulfate and evaporated under vacuum. The residue of 83 mg. of semi-crystalline material contained 61 mg. of formaldehydogenic material. This was chromatographed on silica gel as in Example 1 providing 25 mg. of crystalline corticosterone of practical purity melting above 160° C. and 25 mg. of unaltered desoxycorticosterone melting above 130° C.

Example 4

A solution of 250 mg. of desoxycorticosterone acetate in 2500 cc. of plasma was perfused as in Example 1. The perfusate was treated with 25 g. of activated carbon in two lots at room temperature during about ten hours. The charcoal was washed, dried, and extracted with acetone, methylene chloride and benzene. The bulk of extracted residue (193 mg. out of 256 mg.) was obtained from the methylene chloride extract and was found to contain 164 mg. of formaldehydogenic material. This was chromatographed on silica gel providing 24 mg. of crude crystalline corticosterone and 51 mg. of unaltered desoxy-corticosterone.

Example 5

A solution of 100 mg. of 17-hydroxy-11-desoxycorticosterone in 1000 cc. of citrated isotonic saline containing 10% hemolyzed blood was perfused with venous flow through a lacerated beef adrenal gland using pulsating pressure for 1.5 hours (8 cycles). The perfusate from two such perfusions was treated at room temperature with 40 g. of activated charcoal over a three-day period. The combined charcoal was collected, washed, dried, and exhaustively extracted with methylene chloride. The methylene chloride extract was evaporated under nitrogen at reduced pressure. The extract residue was dissolved in warm ethyl acetate and chilled. Crystalline 17-hydroxycorticosterone was thus obtained. The mother liquors were evaporated under nitrogen at reduced pressure and the residue was taken up in benzene and chromatographed over silica gel. The 17-hydroxycorticosterone was eluted with benzene-ethyl acetate. There was obtained a total of 32.5 mg. of 17-hydroxycorticosterone of practical purity melting above 200° C. together

with a trace of unaltered starting material. The product after further recrystallization from ethyl acetate melted at 207-209° C. The mixed melting point with authentic 17-hydroxycorticosterone isolated from natural sources was not depressed.

Example 6

A solution of 600 mg. of desoxycorticosterone in 3000 cc. of whole blood was perfused with 10 venous flow through a lacerated beef adrenal using non-pulsatile hydrostatic pressure for three hours (1 cycle). The perfusate after hemolysis was treated over a three-day period at room temperature with 60 g. of activated charcoal. Extraction of the charcoal and chromatography of the extracted residue provided 241 mg. of corticosterone of practical purity melting above 160° C. together with 90 mg. of unaltered starting material.

Example 7

A solution of 270 mg. of androsterone in 2700 cc. of plasma was perfused with arterial flow through an intact beef adrenal gland for 6 hours using pulsating pressure. The perfusate was 25 treated with 40 g. of activated charcoal over a three-day period. The charcoals were combined, washed with saline solution and then extracted with methylene chloride for 16 hours in a Soxhlet apparatus. Evaporation of the extract under nitrogen at reduced pressure provided 405 mg. of semi-crystalline material. This residue was dissolved in benzene and chromatographed on silica gel. The column was developed with a benzene-ethyl acetate mixture (20:1) and then the androsterone fraction (125 mg.) was removed by benzene-ethyl acetate (4:1). The column was then eluted with benzene-ethyl acetate (2:1) and this eluate was evaporated giving a residue of 18 mg. of 11-hydroxyandrosterone in non-crystalline form. This residue was dissolved in pyridine and treated with acetic anhydride to form 11-hydroxyandrosterone 3-acetate, which is a crystalline ester. This material was recrystallized from ether and melted at 238-240° C. It was found to be identical with an authentic sample of 11-hydroxyandrosterone 3-acetate by mixed melting point and by infrared absorption spectra.

Example 8

A solution of 750 mg. of desoxycorticosterone in 1000 cc. of plasma containing 20% hemolyzed blood was perfused with venous flow through a lacerated beef adrenal gland using pulsating pressure for 45 minutes (2.5 cycles). The perfusate was treated at room temperature with 20 g. of activated charcoal over a three-day period. The material extracted from the charcoal with methylene chloride weighed 732 mg. and afforded, after chromatography on silica gel, 82 mg. of corticosterone of practical purity melting above 160° C. together with 407 mg. of unaltered starting material.

Example 9

300 mg. of 11-desoxycorticosterone acetate in 16 cc. of propylene glycol and 8 liters of citrated blood as in Example 17 was perfused with arterial flow through an intact beef adrenal gland for 10 hours (one cycle). The perfusate was frozen, thawed, and treated with activated carbon. The carbon was washed with saline and acetone, then extracted in a Soxhlet apparatus for 20 hours with methylene chloride. The methylene chloride extract was evaporated under nitrogen in

vacuo. The residue was dissolved in benzene and passed over 18 g. of silica gel. The column was developed with benzene-ethyl acetate mixtures as in Example 17. There were thus obtained 24 mg. of corticosterone melting at 168-172° C. and 5 95 mg. of desoxycorticosterone melting at 134-138° C., after recrystallization from ethyl acetate.

Example 10.

A solution of 200 mg. of desoxycorticosterone in 2000 cc. of citrated isotonic saline containing 6% of technical blood albumin and 2% of hemolyzed fresh blood was perfused with venous flow through a lacerated beef adrenal gland using pulsating pressure for about two hours (6 cycles). The perfusate was treated with charcoal and the later extracted affording 377 mg. of semi-crystalline residue. This was chromatographed on silica gel yielding 71 mg. of corticosterone of practical purity melting above 160° C. together with 39 mg. of unaltered starting material.

Example 11.

A solution of 91 mg. of desoxycorticosterone in 1000 cc. of a mixture of isotonic saline and Tyrode's solution containing 3% gelatine was perfused with venous flow through a lacerated beef adrenal using pulsating pressure for 1.5 hours (9 cycles). The perfusate was treated with charcoal and the latter extracted affording 110 mg. of semi-crystalline residue. This was chromatographed on silica gel yielding 21 mg. of corticosterone of practical purity melting above 160° C. together with 25 mg. of unaltered starting material.

Example 12.

8 liters of citrated, filtered, whole bovine blood were perfused through two rat livers to remove fibrin. To the blood was added penicillin and streptomycin solution (800,000 units of penicillin G and 800 mg. of streptomycin sulfate in 80 ml. of saline solution) and then 22 ml. of a propylene glycol solution containing 551 mg. of progesterone. The mixture was then perfused 45

individually by centrifugation with five portions of 1% saline solution and two portions of water. All of the washes from the five charcoal fractions were combined and treated with activated carbon, using 5 g. per liter of wash liquor for a total of 25-50 g.

Each of the six activated carbon batches obtained as above was agitated with acetone, filtered and then washed on the filter with copious amounts of acetone. These acetone washes removed the bulk of the water from the charcoal. Each acetone wash or extract was concentrated in vacuo to remove almost all of the acetone, and the residual liquid, which was mainly water was extracted with five portions of chloroform. The combined chloroform extract was concentrated in vacuo to a weighed residue.

Each activated carbon preparation was then washed copiously on the filter with methylene chloride and finally extracted with methylene chloride in a Soxhlet apparatus for 16-24 hours. The methylene chloride solutions from each portion of activated carbon were combined and concentrated in vacuo to weighed residues. After the methylene chloride extractions, the first batch of charcoal was combined with the second, the third with the fourth, and the fifth was combined with the charcoal from the saline washes, and each of the three resulting charcoal preparations was extracted continuously with benzene for 3-5 hours using a modified Soxhlet apparatus. The modification consisted in stirring the charcoal during the extraction and using a plug of glass wool as a filter.

From the six charcoal preparations described above the following weights of material were obtained by the various extraction procedures described above. Each of these residues was tested with concentrated sulfuric acid for green fluorescence, which is an indication of 11-hydroxy steroids such as corticosterone and 17-hydroxy-corticosterone. The following table indicates the weights of materials obtained from the various charcoal fractions by extraction and the results obtained on the concentrated sulfuric acid test:

Batch of carbon	Acetone extract (via chloroform), mg.	Fluorescence with conc. H ₂ SO ₄	Methylene chloride extract, mg.	Fluorescence with conc. H ₂ SO ₄	Benzene extract, mg.	Fluorescence with conc. H ₂ SO ₄
1	112	Strong green	622	Strong green	49	Slight green
2	100	do	392	do		
3	58	Green	393	Trace	59.5	Negative
4	31	Trace	389	Negative		
5	42	do	417	do	91	Do
Saline	16	Negative	42	do		

through four lacerated beef adrenal glands in parallel, the blood entering the venous entry and passing out through the arterial entry, for 3 hours and 11 minutes. This corresponds to 6½ cycles of the blood through the adrenal glands. The blood so obtained amounted to 7,260 ml. and was equivalent to about 500 mg. of progesterone. This blood was frozen to effect hemolysis. The blood was then thawed and treated with five 40-g. portions of activated carbon (Darco G-60). Each treatment consisted in stirring the blood 70 with the charcoal at room temperature for 1-3 hours, allowing the charcoal to settle overnight at room temperature and then separating the supernatant blood by decantation and centrifugation. Each charcoal portion was then washed 75

60 The thimbles and filter papers used in the extractions above were combined and extracted by boiling with two portions of benzene, each for 1 hour. The combined benzene extracts were evaporated in vacuo giving a residue of 23.5 mg. which 65 gave no fluorescence with sulfuric acid. The total weight of extracted material from all of the foregoing procedures was 2837 mg.

The third, fourth, fifth, and sixth methylene chloride extract residues in the above table were combined with the third benzene extract, dissolved in benzene and passed over a column containing 30 g. of silica gel (95% passes through a 100-mesh screen and 90% is retained on a 200-mesh screen). The column of silica gel was then developed by treatment with benzene and

benzene ethyl acetate mixtures according to the following table:

Eluate	Volume (ml.)	Solvent	Weight of residue (mg.)	H ₂ SO ₄ test
1.	80	Benzene	132	
2.	100	Benzene-ethyl acetate (30:1).	687	
3.	100	Benzene-ethyl acetate (20:1).	182	
4.	100	Benzene-ethyl acetate (10:1).	58	Negative.
5.	100	Ethyl acetate	115.5	Do.
6.	100	do	14	Green fluorescence.
7.	100	do	8	Weak fluorescence.
8.	100	Acetone	28	Slight fluorescence.
9.	100	Methanol	25	

Each of these eluates was evaporated in vacuo and each of the residues was given the sulfuric acid test. The results of these tests are indicated in the above table.

A second chromatograph was conducted as follows. The charge consisted of the first and second methylene chloride extract residues. These were dissolved in benzene and passed over a column containing 30 g. of silica gel, as above. The column was then eluted with benzene, benzene-ethyl acetate mixtures, ethyl acetate, acetone and methanol according to the following table:

Eluate	Volume (ml.)	Solvent	Weight of residue (mg.)	H ₂ SO ₄ test
10.	80	Benzene	52	
11.	100	Benzene-ethyl acetate (30:1).	8	
12.	100	Benzene-ethyl acetate (20:1).	179	
13.	100	Benzene-ethyl acetate (10:1).	60	
14.	100	Ethyl acetate	416	Green fluorescence.
15.	100	do	138	Do.
16.	100	do	18.5	Do.
17.	100	do	8	Do.
18.	100	Acetone	41	Do.
19.	100	Methanol	115.5	

Each of the various eluates was evaporated in vacuo and the residue given the sulfuric acid test. Crystallization of the residue from eluate No. 15, which weighed 138 mg., led to 22 mg. of crystalline 17-hydroxycorticosterone melting at 200-201.5° C.

A third chromatograph was carried out using as the charge of the six acetone extracts. These combined residues were dissolved in benzene and passed over 18 g. of silica gel with the following results:

Eluate	Volume (ml.)	Solvent	Weight of residue (mg.)	H ₂ SO ₄ test
20.	80	Benzene	9.5	Negative.
21.	100	Benzene-ethyl acetate (30:1).	34	Do.
22.	100	Benzene-ethyl acetate (20:1).	21	Do.
23.	100	Benzene-ethyl acetate (10:1).	49.5	Do.
24.	100	Ethyl acetate	138	Do.
25.	100	do	15.5	Green fluorescence.
26.	100	do	3.5	Do.
27.	100	do	4	Do.
28.	100	Acetone	32	Do.
29.	100	Methanol	25	

A fourth chromatograph was conducted using as the charge the benzene extracts and 10 g. of silica gel. The following results were obtained:

Eluate	Volume (ml.)	Solvent	Weight of residue (mg.)	H ₂ SO ₄ test
10.	30	Benzene	42	
11.	31	Benzene-ethyl acetate (10:1).	15.5	
12.	32	Benzene-ethyl acetate (9:1).	2.5	
13.	33-36	Benzene-ethyl acetate (8:1).	61	
14.	37-38	Benzene-ethyl acetate (7:1).	2	
15.	39-40	Benzene-ethyl acetate (6:1).	1.5	
16.	41-42	Benzene-ethyl acetate (5:1).	4	
17.	43-45	Benzene-ethyl acetate (4:1).	5	Negative.
18.	46-47	Benzene-ethyl acetate (3:1).	3	Do.
19.	48-49	Benzene-ethyl acetate (2:1).	3	Do.
20.	50-53	Benzene-ethyl acetate (1:1).	5.5	Trace.
21.	54-55	Benzene-ethyl acetate (1:2).	1.5	Negative.
22.	56-57	Benzene-ethyl acetate (1:3).	2.5	Strong fluorescence.
23.	58	Ethyl acetate	7	Slight fluorescence.
24.	59	Acetone	6.5	Negative.
25.	60	Methanol	7	Do.

30

The fifth chromatograph was conducted on 17 g. of silica gel using as the charge the residues from eluates 5 and 24 described above. The following results were obtained.

Eluate	Volume (ml.)	Solvent	Weight of residue (mg.)	H ₂ SO ₄ test
40.	61	Benzene	2.5	
41.	62	Benzene-ethyl acetate (10:1).	3	
42.	63	Benzene-ethyl acetate (9:1).	1	
43.	64-65	Benzene-ethyl acetate (8:1).	20	
44.	66-70	Benzene-ethyl acetate (7:1).	68	
45.	71-73	Benzene-ethyl acetate (6:1).	18.5	
46.	74-76	Benzene-ethyl acetate (5:1).	15.5	
47.	77-79	Benzene-ethyl acetate (4:1).	13.5	
48.	80-84	Benzene-ethyl acetate (3:1).	48.5	
49.	85-87	Benzene-ethyl acetate (2:1).	14	
50.	88-90	Benzene-ethyl acetate (1:1).	15.5	Slight fluorescence.
51.	91-97	Benzene-ethyl acetate (1:2).	41.5	See note.
52.	98	Benzene-ethyl acetate (1:3).	3	Negative.
53.	99	Ethyl acetate	3	
54.	100	Acetone	16	
55.	101	Methanol	6	

NOTE.—Residues 91 and 92 gave a slight fluorescence. 93-95 gave a strong fluorescence. 96-97 were negative.

Eluate	Volume (ml.)	Solvent	Weight of residue (mg.)	H ₂ SO ₄ test
65.	80	Benzene	34.5	
66.	100	Benzene-ethyl acetate (30:1).	21

72.	100	do	32	Do.
73.	100	Acetone	25	
74.	100	Methanol		

65 Crystallization of the residues 81 to 84, which weighed 34.5 mg., from ethyl acetate led to 3.2 mg. of crystalline steroid of unknown structure melting at 202-205° C. The crystallization of residues 93 to 95, weighing 18.5 mg. from a mixture of ethyl acetate and neohexane, led to two crops of crystalline materials, the first weighing 9.5 mg. and melting at 195-197.5° C. and the second weighing 2.9 mg. and melting at 191.5-199° C. 70 Recrystallization of the first crop of crystals

afforded 5.5 mg. of 17-hydroxycorticosterone melting at 207.5-208.5° C.

A sixth chromatogram was conducted using as the charge the residues from eluates 6, 7, 14, 15 (except for the 22 mg. of 17-hydroxycorticosterone obtained from residue 15), 16, 17, 25, 26, and 27. These combined residues were dissolved in benzene and passed over a column of 37.5 g. of silica gel. The column was then eluted with benzene, benzene-ethyl acetate mixtures, ethyl acetate, acetone, and methanol with the following results:

Eluate	Volume (ml.)	Solvent	Weight of residue (mg.)	H ₂ SO ₄ test	15
102	100	Benzene	9.5		136

			180-184	2.2
		136	13.5	17-hydroxycorticosterone.
		137	15	Do.
	20	138	15	Do.
		139	15.5	Mixture of corticosterone and 17-hydroxycorticosterone.
			185-189	3
		140	15.5	17-hydroxycorticosterone.
		141	24.5	Do.
		142	16.5	Do.
		143	11.5	17-hydroxycorticosterone (impure).

Example 13.

8 liters of citrated, filtered, whole bovine blood were passed through two rat livers to remove fibrin. Then a solution of streptomycin and penicillin were added (as in Example 12) followed by 20 ml. of a propylene glycol solution containing 600 mg. of Δ^4 -androstene-3,17-dione. The resulting solution was perfused through four lacerated beef adrenal glands in parallel using venous entry as in Example 12. The perfusion was conducted over a period of 6.5 hours, corresponding to 4½ cycles of the perfusate medium. The perfusate was then frozen to effect hemolysis, thawed, and treated with four portions of activated charcoal (Dacro G-60), each weighing 40 g. Each treatment consisted in stirring the blood with charcoal for 1-3 hours at room temperature, allowing the charcoal to settle overnight at room temperature, separating the supernatant blood by decantation and centrifugation. Each batch of activated carbon was then individually washed by centrifugation with 1% saline solution, repeating this washing generally four or five times.

Each of the four charcoal fractions above was stirred with acetone, filtered, and the filter cake washed copiously with acetone. The filtrate from each of these washings (called the acetone extract) was concentrated in vacuo to dryness. The residue was then extracted with boiling acetone and concentrated in vacuo to a weighed residue. Each batch of charcoal was washed copiously on the filter with methylene chloride and then extracted in a Soxhlet apparatus with methylene chloride for 16-24 hours, then with methanol for 3-4 hours. Each of the extracts was evaporated in vacuo to a weighed residue. The results are set forth in the following table:

70	Activated carbon	Acetone wash, mg.	Methylene chloride wash, mg.	Methylene chloride extract, mg.	Methanol extract, g.
1		117	260	604	1.67
2		284	142	394	0.95
3		219	163	253	0.83
4		127	358	475	

The residues from the first and second methylene chloride washes and the first and second methylene chloride extracts (weighing a total of 1400 mg.) were combined, dissolved in benzene and passed over a column containing 5

then extracted in a Soxhlet apparatus with methylene chloride and finally with benzene, as in Example 12. Each of the extracts was evaporated and the residues were given the sulfuric acid test with the following results:

Extract	Charcoal 1			Charcoal 2			Charcoals 3-5 and saline		
	Hours	Mg.	H ₂ SO ₄	Hours	Mg.	H ₂ SO ₄	Hours	Mg.	H ₂ SO ₄
Acetone (via chloroform).....		103	+		194	+		140	Trace +
Methylene chloride wash.....		134	+		309	-			
Methylene chloride Soxhlet.....	7	299.5	+	2.75	339	Slight +			
Benzene Soxhlet.....	4	76	+	3.75	191	-	13	3,292	-

50 g. of silica gel, as in Example 12. The column was then developed and eluted as follows:

Eluate	Solvent	Volume, ml.	Product
1.....	Benzene-hexane.....	200	Syrup.
2.....	Benzene.....	300	Do.
3.....	Benzene-ether (19:1).....	200	M. P. 52-53° C.
4.....	Benzene-ether (9:1).....	200	Syrup.
5.....	Benzene-ether (4:1).....	400	Do.
6.....	Benzene-ether (3:1).....	600	M. P. 131-132° C.
7.....	Benzene-ether (2:1).....	400	Do.
8.....	Benzene-ether (1:1).....	400	M. P. 225-227° C.
9.....	Benzene-ether (1:2).....	400	Do.
10.....	Benzene-ether (1:3).....	200	M. P. 192-199° C.
11.....	Benzene-ether (1:4).....	200	Do.
12.....	Ether.....	600	Do.
13.....	Ether-ethyl acetate (19:1).....	400	Do.

From the ninth eluate was obtained 21 mg. of 11-β-hydroxy androstane-3,17-dione melting at 226-227° C. (from ether). From the combined tenth, eleventh, twelfth and thirteenth eluates was obtained 162 mg. of 11-β-hydroxy-Δ⁴-androstene-3,17-dione melting at 197-199° C. (from ether-pentane). These substances had respectively the following rotations: $[\alpha]_D^{30} = +96^\circ$ (c=0.426; CHCl₃) and $[\alpha]_D^{30} = +208^\circ$ (c=0.393; CHCl₃). The former was converted into androstan-3,11,17-trione, M. P. 178-180° C., identical with an authentic sample. The latter was converted to andrenosterone, M. P. 220-222° C., identical with an authentic sample.

Example 14

To 8 liters of citrated, filtered, defibrinated, whole bovine blood containing penicillin and streptomycin as in Example 12 was added a solution of 200 mg. of pregnenolone (Δ^5 -pregnen-3 β -ol-20-one) in 15 ml. of propylene glycol. The mixture was perfused through three lacerated beef adrenal glands in parallel using venous entry for 200 minutes, which corresponds to eight cycles of the fluid. The perfusate fluid (7700 ml., equivalent to 192 mg. of pregnenolone) was frozen to effect hemolysis and then thawed. The blood was then treated with five 40-g. portions of activated carbon (Darco G-60) as in Example 12. After the second charcoal treatment 5 g. of sodium fluoride were added to suppress mold growth. Each of the five charcoal batches was washed with saline solution and with acetone as in Example 12. The saline washes were combined and treated with activated charcoal (5 g. per liter). The acetone washes were evaporated, the aqueous residues extracted with chloroform, and the chloroform extract of each batch was evaporated to a weighed residue. The batches of activated carbon were washed with methylene chloride and 75

20 The total amount of solids obtained from these extracts was 5109.5 mg. This includes 32 mg. of material giving a negative sulfuric acid test, which was obtained by extracting the filter papers and thimbles with benzene.

25 The acetone extracts of the third, fourth, and fifth charcoals and the charcoals from the saline washes and from all of the benzene extracts were combined, dissolved in benzene, and chromatographed over a column of 80 g. of silica gel as in Example 12. The column was developed and eluted with benzene, benzene-ethyl acetate mixtures, acetone and methanol with the following results:

35	Eluate	Volume, ml.	Solvent	Residue, mg.
1.....		150	Benzene.....	
2.....		250	Benzene-ethyl acetate (10:1).....	
3.....		100	do.....	
4.....		100	do.....	
5.....		100	do.....	
6.....		100	Benzene-ethyl acetate (8:1).....	34.1
7.....		100	Benzene-ethyl acetate (6:1).....	18.8
8.....		100	Benzene-ethyl acetate (4:1).....	20.2
9.....		250	Ethyl acetate.....	67.4
10.....		250	do.....	516.6
11.....		250	do.....	25.8
12.....		100	do.....	18.5

15.....		150	Methanol.....	36.0
16.....		150	do.....	61.9
				8.8

50 A second chromatogram was carried out as above using as the charge the residues from eluates 6 to 9, inclusive, of the foregoing chromatogram and 30 g. of silica gel. The following results were obtained:

60	Eluate	Volume, ml.	Solvent	Residue, mg.
17.....		75	Benzene.....	8.9
18.....		50	Benzene-ethyl acetate (10:1).....	1.5
19.....		50	Benzene-ethyl acetate (8:1).....	6.2
20-26.....		7X50	Benzene-ethyl acetate (6:1).....	313.9
27-29.....		3X50	Benzene-ethyl acetate (4:1).....	36.0
30-35.....		3X50, 75, 50	Benzene-ethyl acetate (3:1).....	112.9
36-39.....		4X50	Benzene-ethyl acetate (2:1).....	20.8
40-42.....		3X50	Benzene-ethyl acetate (1:1).....	19.2
43-49.....		3X50	Benzene-ethyl acetate (1:2).....	10.8
46-48.....		3X50	Benzene-ethyl acetate (1:3).....	4.7
49-51.....		3X50	Ethyl acetate.....	5.7
52.....		50	Acetone.....	5.3
53.....		100	Methanol.....	12.0

70 A third chromatogram was conducted on 60 g. of silica gel using as the charge all of the methylene chloride extracts of the first and second batches of activated carbon and residues 10 to

16. inclusive, of the first chromatogram in this example. The following results were obtained:

Eluate	Volume, ml.	Solvent	Residue, mg.
54	100	Benzene	187.5
55-59	5×75	Benzene-ethyl acetate (2:1)	825.9
60-68	7×75	Benzene-ethyl acetate (10:1)	186.4
67-69	3×75	Benzene-ethyl acetate (9:1)	27.4
70-76	7×75	Benzene-ethyl acetate (8:1)	75.3
77-81	5×75	Benzene-ethyl acetate (7:1)	20.9
82-84	3×75	Benzene-ethyl acetate (6:1)	10.8
85-88	4×75	Benzene-ethyl acetate (5:1)	22.0
89-93	5×75	Benzene-ethyl acetate (4:1)	40.8
94-99	6×75	Benzene-ethyl acetate (3:1)	47.3
100-106	7×75	Benzene-ethyl acetate (2:1)	50.7
107-123	17×75	Benzene-ethyl acetate (1:1)	200.0
124-128	5×75	Benzene-ethyl acetate (1:2)	33.2
129-133	5×75	Benzene-ethyl acetate (1:3)	21.5
134-136	4×150	Ethyl acetate	41.9
137-139	3×150	Acetone	103.2
140	150	Methanol	71.8

Crystalline materials were obtained from various eluates, using as crystallization media ethyl acetate or acetone, alone or with neohexane. The following results were obtained:

Residue	Weight, mg.	M. P. of solid obtained, °C.	Weight, mg.	Identity
109	9.2	104-104.5	0.5	
111	16.8	167-182	6.8	Corticosterone.
112	16.3	174-181	6.2	Do.
113	14.2	175-181	3.2	Do.
115	17.5	173-181	5.4	Do.
116	19.0	195-196	5.2	Impure 17-hydroxycorticosterone.
117	13.8	194-196	3.7	Do.
118	11.7	196-197	3.2	17-hydroxycorticosterone.
119	9.2	192-200	2.3	Do.
Mother liquor residues from 115-118.	44.7	152.5-153	1.1	
135	15.1	220	0.7	
136	13.6	220	0.8	

Example 15

8 liters of citrated, defibrinated, filtered, whole bovine blood containing streptomycin and penicillin prepared as in Example 12 was treated with a solution of 934 mg. of 17-hydroxyprogesterone in propylene glycol and then perfused through four lacerated beef adrenal glands in parallel for 3½ hours using venous entry. This corresponds to two actual cycles of the fluid. 7340 ml. of perfusate fluid (corresponding to 852 mg. of 17-hydroxyprogesterone) was frozen, thawed and treated with 40-g. portions of activated charcoal at room temperature. The various charcoal 55 preparations were washed or extracted with acetone, methylene chloride and benzene as in Example 12 with the following results.

18 all extracts of the remaining batches of charcoal. The following results were obtained:

Eluate	Volume (ml.)	Solvent	Weight of residue (mg.)
5	175	Benzene	135
1	2, 3	Benzene-ethyl acetate (30:1)	274.5
2	2×100	Benzene-ethyl acetate (20:1)	11.5
4, 5	2×100	Benzene-ethyl acetate (10:1)	1,489
6-8	3×100	Benzene-ethyl acetate (2:1)	137
9	100	Benzene-ethyl acetate (1:1)	189
10	100	Benzene-ethyl acetate (1:2)	110
11	100	Benzene-ethyl acetate (1:3)	57
12	100	Ethyl acetate	189.5
13-16	4×100	Acetone	101
17	100	Methanol	133
15			

A second chromatogram was conducted using 72 g. of silica gel and the acetone and the methylene chloride extracts of the first activated carbon. The following results were obtained:

Eluate	Volume (ml.)	Solvent	Weight of residue (mg.)
25	50	Benzene	34.5
19	2×50	Benzene-ethyl acetate (30:1)	7
20-21	2×50	Benzene-ethyl acetate (20:1)	4.5
22-23	3×50	Benzene-ethyl acetate (10:1)	69.5
24-26	3×50	Benzene-ethyl acetate (9:1)	51
27-28	2×75	Benzene-ethyl acetate (8:1)	25
29-30	2×75	Benzene-ethyl acetate (7:1)	11.5
31-32	3×75	Benzene-ethyl acetate (6:1)	10.5
33-35	3×75	Benzene-ethyl acetate (5:1)	13.5
36-38	3×75	Benzene-ethyl acetate (4:1)	556.9
39-53	15×75	Benzene-ethyl acetate (3:1)	68.8
54-64	11×75	Benzene-ethyl acetate (2:1)	23.4
65-69	5×75	Benzene-ethyl acetate (1:1)	63.5
70-78	9×75	Benzene-ethyl acetate (1:2)	70.5
79-87	9×75	Benzene-ethyl acetate (1:3)	12.3
88-91	4×75	Benzene-ethyl acetate (1:4)	5.0
92-93	2×75	Benzene-ethyl acetate (1:6)	5.2
94-95	2×75	Ethyl acetate	12.2
96-98	3×100	Acetone	41.4
99-101	3×100	Methanol	62.9
102-104	3×100		

40 Various crystalline products were obtained from the foregoing eluates using ethyl acetate as the crystallization solvent. The following results were obtained:

Eluate	Weight (mg.)	M. P. of solid obtained, °C.	Weight crystalline material (mg.)	Identity
45				
50	478.5	212.5-215	421.3	17-hydroxyprogesterone.
49	20.5	211-216	12.4	Do.
50	17.2	208-214	7.2	Do.
51	12.0	209-212	4.2	Do.
52	10.6	203-208	6.5	Do.
56-60	38.2	193-195	8.9	
80-82	34.2	184-186	18.5	17-hydroxycorticosterone.
83	8.4	186-189	3.2	

Example 16
7 liters of filtered, defibrinated, whole bovine

Charcoal	1	2	3	4	5	Saline
Acetone extract (via chloroform)	323 mg.	60.5 mg.	32 mg.	88.5 mg.	100 mg.	34 mg.
Fluorescence with cone. H_2SO_4	Strong +	Positive	Slight +	Negative	Negative	Negative

Benzene (Soxhlet)	44 mg.	27.5 mg.	67.5 mg.		59.5 mg.	Slight
H_2SO_4 test	Positive					

Benzene extraction of all thimbles and filter papers yielded 18.5 mg. of material which gave a slight fluorescence with concentrated sulfuric acid. The total extracted material was 4064 mg.

A chromatogram was conducted on 140 g. of silica gel as in Example 12 using as the charge the benzene extract of the first bath of charcoal and

70 blood were mixed with 3 liters of citrated saline solution (0.8% sodium chloride and 0.45% sodium citrate hydrate). Then 1,000,000 units of penicillin G and 1 g. of streptomycin sulfate in saline solution are added. To this medium was added a solution of 2000 mg. of 11-desoxy-17-hydroxycorticosterone in 150 ml. of propylene

glycol. This solution was perfused through ten lacerated beef adrenal glands in parallel using venous entry for a total period of 7 hours, which corresponds to eleven cycles of the perfusion fluid. The citrated blood was removed from the perfusion apparatus and passed through a colloid mill to hemolyze the cells. 8.60 liters of the perfusion fluid (equivalent to 1720 mg. of 11-desoxy-17-hydroxy-corticosterone) were treated with three 50-g. portions of activated carbon (Darco G-60) as in Example 12. The three charcoal batches were combined, washed with saline solution and then with a minimum of acetone to remove water. The charcoal was then extracted in a Soxhlet apparatus with 3 liters of methylene chloride for a period of 20 hours. The methylene chloride solution was then evaporated in vacuo under nitrogen. The residue of steroid material was crystallized from 50 cc. of ethyl acetate. There was obtained in this way 413 mg. of 17-hydroxycorticosterone which melts at 208-210° C.

The mother liquors from the foregoing crystallization were evaporated in vacuo under nitrogen and the residual steroid mixture was taken up in 150 ml. of benzene-ethyl acetate (9:1) and passed over a column of 80 g. of silica gel. The column was developed with 600 ml. of benzene-ethyl acetate (4:1) and eluted with 550 ml. of benzene-ethyl acetate (1:1), followed by 250 ml. of benzene-ethyl acetate (2:3) and then 750 ml. of ethyl acetate. The eluates were evaporated under nitrogen at reduced pressure, and the residues were crystallized from ethyl acetate. In this way an additional crop of crystalline 17-hydroxycorticosterone, weighing 327 mg., was obtained from the ethyl acetate eluate, as well as 240 mg. of 11-desoxy-17-hydroxycorticosterone from the benzene-ethyl acetate (1:1). The total yield of 17-hydroxycorticosterone was 740 mg., which is equivalent to 50% of theory based on the amount of starting material consumed.

Example 17

3 liters of citrated, filtered, defibrinated, whole bovine blood containing penicillin and streptomycin as in Example 12 were treated with a solution of 600 mg. of 11-desoxycorticosterone in 45 ml. of propylene glycol. The resulting solution was perfused through eight lacerated beef adrenal glands for 4 hours (equivalent to 9.3 cycles). The blood was then hemolyzed by thawing and freezing. 2.88 liters of the perfusion liquid were treated with three 15-g. portions of activated carbon and the three batches of carbon were combined, washed with saline and a minimum of acetone and then extracted in a Soxhlet apparatus with methylene chloride for 20 hours. The methylene chloride extract was evaporated in vacuo under nitrogen and the residue was taken up in 70 cc. of benzene-ethyl acetate (9:1). This solution was passed over a column containing 35 g. of silica gel. The column was developed with 250 ml. of benzene-ethyl acetate (4:1). The column was then eluted with 250 cc. of benzene-ethyl acetate (2:1) which removed most of the desoxycorticosterone. This eluate was evaporated under vacuo in nitrogen and the residual steroid was recrystallized from ether, yielding 42 mg. of desoxycorticosterone melting at 134-137° C. The column was then eluted with 75 cc. of benzene-ethyl acetate (1:1). This eluate was evaporated in vacuo under nitrogen and the steroid residue was tested with concentrated sulfuric acid. Residues which

gave a greenish fluorescence were crystallized from ether and material melting in the range of 160-170° C. was recovered as corticosterone. Material melting in the range of 130-140° C. was recovered as unchanged starting material. The column was finally eluted with 300 cc. of ethyl acetate. This eluate was evaporated in vacuo under nitrogen and the residue was crystallized from a mixture of ethyl acetate and petroleum ether. Three batches of crystalline corticosterone melting respectively at 169-172° C., 165-168° C. and 160-164° C. were obtained, weighing a total of 220 mg., which represents a yield of 41% of theory on the basis of unrecovered starting material.

Example 18

300 mg. of 11-desoxy-17-hydroxycorticosterone 21-acetate dissolved in 10 ml. of propylene glycol was added to 3 liters of citrated whole bovine blood containing 300,000 units of penicillin G and 300 mg. of streptomycin sulfate. The resulting fluid was perfused through an intact beef adrenal gland, using arterial flow for 10 hours (one cycle). The blood was frozen, thawed, and treated successively with three 15-g. portions of activated carbon. The activated carbon batches were combined, washed with saline solution and with a minimum of acetone. The carbon was then extracted exhaustively in a Soxhlet apparatus with methylene chloride for 20 hours. The methylene chloride extract was evaporated in vacuo under nitrogen. The residue was taken up in benzene-ethyl acetate (9:1) and passed over a column of 18 g. of silica gel. The column was eluted with benzene-ethyl acetate and ethyl acetate as in Example 16. From the ethyl acetate eluate was obtained crystalline 17-hydroxycorticosterone (25 mg.) melting at 208-210° C. after recrystallization from ethyl acetate. From the benzene-ethyl acetate (1:1) eluate was obtained 110 mg. of 11-desoxy-17-hydroxycorticosterone.

We claim:

1. The method of hydroxylating a steroid 45 which comprises adding a member of the group of steroids having one of the following formulas:

and

70 wherein X and Z are members of the group consisting of hydroxyl and oxo radicals, Y is a member of the group consisting of hydrogen and hydroxyl radicals, and R is a member of the group consisting of hydrogen, hydroxyl and lower aliphatic acyloxy radicals, and wherein said

21

steroid may contain a double bond at position 5, to a fluid selected from blood, blood components, blood substitutes and mixtures thereof with aqueous salt solutions, perfusing a functioning, excised, mammalian adrenal gland with said fluid, said adrenal gland being so incised as to penetrate superficial layers without cutting the medullary layer and being structurally intact, and subsequently isolating the hydroxylated steroids from said fluid.

2. The method of claim 1 wherein the steroid is 11-desoxycorticosterone.

3. The method of claim 1 wherein the steroid is 11-desoxy-17-hydroxycorticosterone.

4. The method of claim 1 wherein the steroid is progesterone.

5. The method of claim 1 wherein the steroid is Δ^4 -androstene-3,17-dione.

6. The method of claim 1 wherein the steroid is 17-hydroxyprogesterone.

7. The method of producing corticosterone which comprises perfusing a functioning, excised, mammalian adrenal gland with blood plasma containing 11-desoxycorticosterone, said adrenal gland being so incised as to penetrate superficial layers without cutting the medullary layer and being structurally intact, and subsequently isolating corticosterone from said plasma.

8. The method of producing 17-hydroxycorticosterone which comprises perfusing a functioning, excised, mammalian adrenal gland with blood plasma containing 11-desoxy-17-hydroxycorticosterone, said adrenal gland being so incised as to penetrate superficial layers without cutting the medullary layer and being structurally intact, and subsequently isolating 17-hydroxycorticosterone from said plasma.

9. The method of hydroxylating progesterone which comprises perfusing a functioning, excised, mammalian adrenal gland with blood containing progesterone, said adrenal gland being so incised as to penetrate superficial layers without cutting the medullary layer and being structurally intact,

22

and subsequently isolating the hydroxylated steroids from said blood.

10. The method of producing 11-hydroxy- Δ^4 -androstene-3,17-dione which comprises perfusing a functioning, excised, mammalian adrenal gland with blood containing Δ^4 -androstene-3,17-dione, said adrenal gland being so incised as to penetrate superficial layers without cutting the medullary layer and being structurally intact, and subsequently isolating 11-hydroxy- Δ^4 -androstene-3,17-dione from said blood.

11. The method of producing 17-hydroxycorticosterone which comprises perfusing a functioning, excised, mammalian adrenal gland with blood containing 17-hydroxyprogesterone, said adrenal gland being so incised as to penetrate superficial layers without cutting the medullary layer and being structurally intact, and subsequently isolating 17-hydroxycorticosterone from said blood.
